UNITED STATES PATENT OFFICE

JOHN FORST, OF NEW YORK, N. Y., ASSIGNOR TO MANHATTAN WICKER CO., OF NEW YORK, N. Y., A CORPORATION OF NEW YORK

DESIGN FOR A RECLINING ARMCHAIR

Application filed June 27, 1930. Serial No. 36,208. Term of patent 3½ years.

To all whom it may concern:

Be it known that JOHN FORST, a citizen of the United States, and resident of New York in the county of New York and State of New York, has invented a new, original, and ornamental Design for a Reclining Armchair, of which the following is a specification, reference being had to the accompanying drawing, forming part thereof, in which the figure is a perspective view of the reclining armchair, embodying my new design.

I claim:

The ornamental design for a reclining arm chair, as shown.

Dated, New York city, 26th day of June, 1930.

JOHN FORST.
